UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

BLINDSTITCH DEVICE FOR SEWING-MACHINES.

1,320,457.

Specification of Letters Patent.

Patented Nov. 4, 1919.

Application filed January 2, 1917. Serial No. 140,122.

To all whom it may concern:

Be it known that I, ALBERT H. DE VOE, a citizen of the United States, residing at Westfield, in the county of Union and State 5 of New Jersey, have invented certain new and useful Improvements in Blindstitch Devices for Sewing-Machines, of which the following is a specification, reference being had therein to the accompanying drawings.

10 This invention relates to sewing machines equipped for blind-stitching and has for an object to provide a machine which will simultaneously stitch upper and lower plies of fabric together or to the opposite faces of 15 intermediate material in such a manner that the connecting portions of the stitching thread or threads between adjacent needle-punctures will not be visible at either side of the seam.

20 More specifically the invention has for an object to provide a machine which will simultaneously blind-stitch upper and lower tapes together at their opposite margins to form a tubular structure, or to blind-stitch 25 said tapes to the opposite faces of intermediate body-fabric which may include a previously formed seam, to be covered by said tapes, or which may present overlapping or abutted edge-portions to be simultaneously 30 joined and covered by said tapes as they are stitched together.

A further object of the invention is to provide means for producing a fullness in a strip of material after it has passed over an 35 inverting edge to compensate for any undue stretching of the material and to insure that said material will be stitched to the body-fabric in normal or unstretched condition. The invention also contemplates the adjustment 40 of said means to produce more than enough fullness to compensate for any stretching of the material, whereby the latter may, if desired, be stitched to the body-fabric in a ruffled condition.

45 A further object of the invention is to provide means for pulling the upper and lower strips of material from the supply.

50 Further objects of the invention will appear from the following description and claims.

The invention, in its preferred embodiment, comprises a sewing machine of the

usual flat-bed type having a cloth-plate over which is disposed the usual head carrying a presser-bar and reciprocating needle-bar 55 whose lower end terminates in a laterally extended needle-clamp carrying spaced eye-pointed needles which co-operate with any suitable type of loop-taker mechanism, in the usual manner to form spaced rows of 60 stitches. Secured to the presser-bar is a presser-foot whose shank is formed with a tape-guiding slot and whose sole-portion is formed with a transversely extending tape-inverting edge which is spaced above the fabric-engaging surface of the presser-foot and is disposed in rear of and closely adjacent the paths of the needles.

Co-operating with the fabric-engaging surface of the presser-foot to feed the work is 70 any suitable type of feeding mechanism which may comprise a four-motion feed-dog operating through a slotted throat-plate. In the present instance the throat-plate is provided with a narrow transversely extending slot whose opposite end-portions receive the descending needles and whose rear edge-wall serves to invert a tape drawn forwardly beneath the throat-plate and upwardly through said needle-receiving slot. The rear 75 edge-wall of the needle-receiving slot and the transversely extending forward edge of the presser-foot define a plane which is disposed parallel to and closely in rear of the plane of the needles, whereby the needles 80 will split the upper and lower thicknesses of tape presented by the tape-inverting elements and connect said tapes by spaced rows of blind-strokes.

The presser-foot carries an adjustable, 90 forwardly disposed, fulling or ruffling blade which is actuated by the needle-bar and is directed rearwardly to engage the upper tape between the inverting element and the last stitch and to full in said tape to the 95 extent desired. A pull-off bar carried by the presser-foot and actuated by the needle-bar is adapted to draw the material closely about said element, to insure accurate splitting thereof by the needles, and to pull the 100 material from the supply. Preferably, the fulling blade is first actuated to engage and full in the material below the inverting element after which the pull-off bar is actuated

to draw back any excess of material while holding the latter close to said inverting edge.

The feed-dog of the machine is slotted to 5 guide the lower tape and its rising and falling motion is taken advantage of to pull a length of lower tape from the supply prior to each feeding stroke in order that the tape may run freely over the lower inverting element 10 without becoming unduly stretched or offering undue resistance to the action of the feeding mechanism.

In the accompanying drawings forming a part of this specification, Figure 1 is a 15 perspective view of the machine showing the work in place. Fig. 2 is a left side elevation, partly in section, with the needles at their highest point. Fig. 3 is a similar view with the needles at their lowest point. Fig. 20 4 is an enlarged cross sectional view through the presser-foot and throat-plate. Fig. 5 is a front view showing the presser-foot in elevation and the throat-plate and feed-bar in section. Fig. 6 is a horizontal section of 25 the presser-foot and needles on the line 5—5, Fig. 5. Fig. 7 is a bottom plan view of the presser-foot. Fig. 8 is a plan view of a portion of the throat-plate. Fig. 9 is an enlarged sectional view similar to Fig. 4 but 30 showing a modification of the invention and Fig. 10 is a perspective view of a seam formed by the machine.

In the embodiment illustrated, the invention comprises a flat-bed sewing machine of 35 usual construction having a cloth-plate 1 over which is disposed the head 2 carrying the usual spring-pressed presser-bar 3 and reciprocating needle-bar 4 whose lower extremity is extended laterally to form a 40 needle-clamping head 5 in which are secured, in spaced relation, the eye-pointed needles 6 which may coöperate with any of the well-known loop-taker mechanisms to produce spaced rows of stitches.

45 Secured to the presser-bar 3 by the screw 7 is the slotted lug 9 which projects rearwardly from a tape-guiding frame comprising a vertical plate 10 whose lower end-portion together with the lug 9 form the shank 50 of a presser-foot 11.

Secured within a recess in the bottom face of the presser-foot 11 by a screw 12 is a flat guide-block 13 whose forwardly disposed marginal portion is undercut at 13' 55 to form a thin overhanging blade 14 whose forwardly disposed edge-portion 14' may be considered as a tape-inverting element which is spaced above the plane of the fabric-engaging surface of the presser-foot and 60 is disposed in a vertical plane at right angles to the line of feed and closely adjacent and parallel to the plane of the needles 6. The lower front corner 15 of the guide-block 13 forms another tape-guiding element spaced 65 below and rearwardly from the tape-invert-

ing element 14 for a purpose to be described. The thickness of the guide-block 13 is made less than the depth of the recess into which it is fitted to provide a tape-receiving guide-way 16 in the bottom face of the presser- 70 foot.

Extending forwardly at opposite sides of the presser-foot and at opposite ends of the tape-inverting element 14' are the spaced overhanging toe-portions 17 which serve as 75 edge-guides for the upper tape. The toe-portions 17 are disposed above the plane of the bottom surface of the presser-foot 11 to permit passage of the reciprocatory fulling or ruffling blade 18 beneath the inverting element 14' and across a plane defined by said element 14' and the corner 15, to full in or ruffle the tape.

The fulling or ruffling blade 18, which may or may not be toothed at its active edge 19, is carried at the lower reversely curved end of a lever 20 pivoted at its upper end between the spaced ears 21 projecting upwardly from the plate 10. Pivoted to the lever 20 at 22 is a bar 23 whose slotted lower end portion is secured in adjusted position against the side face of the lever 20 by a screw 24. A pair of coil-springs 25 projecting forwardly from suitable sockets in the plate 10, urge said lever to the position shown in Fig. 2. As the needle-bar descends the needle-clamping head 5 will strike the inclined front edge 26 of the adjustable bar 23 and force the fulling lever 20 to the position shown in Fig. 3. The length of the fulling or ruffling stroke of the blade 18 may obviously be varied by adjusting the bar 23 upon the lever 20. Spaced guide-lugs 27, projecting forwardly from the plate 10, 95 serve to guide the lever 20 in its to-and-fro movements.

Acting upon the tape above the inverting element 14' is a pull-off device comprising a pull-off lever 28 whose upper end is pivoted at 29 to the plate 10 and whose lower or active portion 28' is bent to assume a substantially horizontal position transversely of and above the sole-portion of the presser-foot 11. A coil-spring 30, projecting forwardly from a suitable socket in the plate 10, urges the pull-off bar 28 to initial position, as shown in Fig. 2. The head 5 after having deflected the fulling lever 20 to a position in which the front edge 26 of the adjustable bar 23 is parallel to the path of reciprocation of said head, strikes the pull-off lever 28 and deflects it rearwardly thus causing the horizontal or active portion 28' of said lever to deflect the upper tape *t* at a point between the tape-guiding aperture 31 and the tape-inverting element 14'. Deflection of the tape *t* at this point serves to draw said tape snugly against the inverting edge 14' for penetration by the needles 6 and also serves to pull a length of 130

tape from the supply through the aperture 31. The horizontal portion 28' of the pull-off lever 28 is notched at 32 to receive the needles during the first part of their down stroke.

In the present construction provision is made for passage of the under tape *t'* forwardly beneath the cloth-plate 1 and upwardly about the rear edge wall of a transverse needle-receiving slot. Supported by the cloth-plate 1 is the throat-plate 33 formed with feed-dog receiving slots 34 and transversely recessed in front of said slots to receive an auxiliary throat-plate 35 provided with a narrow slot 36 to receive the needles 6 and under tape *t'*. The rear edge-wall 37 of the slot 36 constitutes an under tape-inverting element which is parallel with the upper inverting element 14' and, like the latter, is located substantially at the stitching point. In other words, the tape-inverting elements 37 and 14' define a plane which is parallel to and closely adjacent the plane of the needles 6. Screwed to the under surface of the auxiliary throat-plate 35 is a tape-supporting plate 38, Fig. 4, whose rear edge-portion extending under the slot 36 is beveled at 39 and notched at 40, 40, Fig. 8, to receive the needles 6. The beveled edge-portion 39 serves to support the tape *t'* close to the under surface of the auxiliary throat-plate 35 and causes said tape to be bent sharply about the inverting element 37.

Means are provided for pulling the under tape *t'* from the supply in order that said tape may be free to be drawn upwardly through the slot 36 when the work is fed. In the present embodiment the usual four-motion feed-bar 41 carrying the feed-dog sections 42 is formed with a substantially horizontal tape-guiding slot 43 extending under said feed-dog sections 42 and serving to guide the tape running forwardly through the passageway 44 beneath the cloth-plate 1. When the feed-bar drops at the end of a feeding stroke it will deflect the length of tape *t'* between the passageway 44 and slot 37 and pull a length of tape from the supply through said passageway. When the feed-bar rises from the position shown in Fig. 3 to begin a feeding stroke the tape will be loosened to be freely drawn through the slit 36 as the work is fed.

In the modification of the invention illustrated in Fig. 9 the tape-engaging element 15', which is analogous to the corner 15 in Fig. 4, is projected forwardly beneath the tape-inverting element 14'. The tape-guiding elements 14' and 15' are spaced apart and are both carried by the block 13^x which in other respects is similar in construction to block 13, Fig. 4. The fulling blade 18' is adapted to pass between said elements and is provided with a non-toothed tape-engaging edge 18^x. In this form of the invention

the fulling action of the blade is obviously increased and amounts practically to a ruffling action.

While the machine is obviously operative without the described tape-fulling and pull-off devices, the provision of some such devices is desirable in order that tape which stretches easily, such as bias woven tape, may be incorporated in the finished seam in a normal or unstretched condition. The fulling blade 18 accomplishes this result with regard to the upper tape *t*. The pull-off devices serve to supply loose tape to avoid undue stretching thereof when drawn over the inverting elements 14' and 37 during a feeding action. Said devices also serve to draw the tapes snugly about the inverting elements for presentation to the descending needles. When it is desired to simultaneously join and cover the marginal portions of two pieces of body-fabric the machine may be provided with a fabric guide, such as the folder *f*, to present said marginal portions to the needles.

In Fig. 10, which illustrates a seam formed by the above described mechanism, the marginal portions *a* and *a'* of the pieces of body fabric are folded inwardly and joined by means of the upper and lower tapes *t* and *t'* which are connected together by the spaced rows of stitches comprising spaced series of keyed, penetrative, thread-loop structures *s* and connecting thread portions *s'* extending along the hidden surfaces of said tapes. Each of the penetrative thread-loop structures *s* passes through the intermediate body-fabric material and enters and emerges from the inner or hidden surfaces of the upper and lower plies of material *t* and *t'*, preferably without showing at the outer or visible surfaces thereof.

It is to be understood that the form and arrangement of the various parts disclosed are susceptible of material modification without departure from the invention.

Having thus set forth the nature of the invention, what I claim herein is:—

1. In a sewing machine, in combination, stitch-forming mechanism including a reciprocating needle, feeding mechanism, and upper and lower tape-inverting elements having tape inverting edge-portions located substantially at but slightly in rear of the stitching point in a plane parallel to the needle and at substantially right angles to the line of feed.

2. In a sewing machine, in combination, stitch-forming mechanism including spaced parallel reciprocating needles, feeding mechanism, and upper and lower tape-inverting elements having tape inverting edge-portions disposed in a plane in rear of and closely adjacent the plane of said needles.

3. In a sewing machine, in combination, stitch-forming mechanism including a nee-

dle, feeding mechanism, a guide-frame having a forwardly disposed edge about which the material to be stitched is supported for penetration by said needle, and means 5 moving in the direction of feed to full in said material between said edge and the last stitch.

4. In a sewing machine, in combination, stitch-forming mechanism including a needle, 10 feeding mechanism, forwardly directed means located substantially at but slightly in rear of the stitching point for inverting a layer of fabric, and fulling in means acting in the direction of feed on the inverted 15 portion of said fabric between the inverting means and the stitching point before it is stitched.

5. In a sewing machine, in combination, a throat-plate, stitch-forming mechanism 20 including a needle, feeding mechanism, separate elements located above and below the plane of said throat-plate and substantially at the stitching point for inverting upper and lower plies of fabric, and fulling in 25 means acting on the inverted portion of one of said plies before it is stitched.

6. In a sewing machine, in combination, stitch-forming mechanism including a reciprocating needle, a presser-member having 30 a work-engaging surface and formed with an edge-portion extending transverse to the line of feed about which the material to be stitched is folded for penetration by said needle, and a fulling device acting upon the 35 material between said edge-portion and work-engaging surface.

7. In a sewing machine, in combination, stitch-forming mechanism including a reciprocating needle, feeding mechanism, 40 means located substantially at the stitching point for inverting upper and lower strips of fabric, and pull-off devices acting, respectively, on each of said strips between said inverting means and the supply.

8. In a sewing machine, in combination, stitch-forming mechanism including a reciprocating needle, feeding mechanism, means including a plate having a forwardly disposed edge located substantially at the 50 stitching point for inverting a strip of fabric, a fulling device acting in the direction of feed upon said strip between said inverting means and the last stitch, and a pull-off device acting upon said strip between said inverting means and the supply.

9. In a sewing machine, in combination, stitch-forming mechanism including a reciprocating needle, feeding mechanism, a 60 guide-frame having a forwardly disposed edge over which the material to be blind-stitched is drawn, and a fulling device positioned to act in the direction of feed upon the material between said edge and the stitched portion of the work.

10. In a sewing machine, in combination,

stitch-forming mechanism including a reciprocating needle, feeding mechanism including a work-engaging member, a presser-member cooperating with said feeding member to feed the work and presenting 70 an edge over which the material to be blind-stitched is drawn for penetration by said needle, and a fulling device acting upon the material between said edge and work-engaging member.

11. In a sewing machine, in combination, a reciprocating needle, feeding mechanism including a work-engaging member, a presser-member presenting an edge over which the material to be blind-stitched is 80 drawn for penetration by said needle, and a reciprocating fulling member acting upon the material between said edge and work-engaging member and timed to engage and full in the material prior to penetration thereof by said needle.

12. In a sewing machine, in combination, feeding mechanism including a feed-dog, a presser-foot formed with a tape-inverting edge, a reciprocating blade pivotally mounted upon said presser-foot and adapted to engage and full in the tape below said edge, and stitch-forming mechanism including a needle adapted to reciprocate in a path closely adjacent said edge.

13. In a sewing machine, in combination, stitch-forming mechanism including a needle, feeding mechanism, a presser-foot supported in rear of said needle and having an edge-portion for inverting a strip of material while presenting it to said needle, and a reciprocating fulling blade adapted to pass beneath said inverting edge-portion at the end of its fulling stroke.

14. In a sewing machine, in combination, a reciprocating needle-bar carrying a needle, a presser-foot having an edge about which the material to be blind-stitched passes, a fulling member pivotally mounted on said presser-foot and having a blade disposed in advance of and adapted to pass beneath said edge, and actuating connections between said needle-bar and fulling member.

15. In a sewing machine, in combination, stitch-forming mechanism including a reciprocating needle, a presser-member having spaced work-guiding surface-portions one of which is disposed closely adjacent the needle-path, whereby the material to be blind-stitched is presented for penetration by the 115 needle, and a fulling device having an operative edge adapted to cross a line connecting said surface portions.

16. In a sewing machine, in combination, stitch-forming mechanism including a reciprocating needle, feeding mechanism, a throat-plate having a needle-aperture through which the material to be stitched passes upwardly and is presented in a transversely folded condition for penetration by 125 130

said needle, and means sustained below said aperture for supporting the fold of material against the thrust of said needle.

17. In a sewing machine, in combination, 5
stitch-forming mechanism including a reciprocating needle, feeding mechanism, a throat-plate having a needle aperture through which the material to be stitched passes upwardly and is presented in a trans-
10 versely folded condition for penetration by said needle, and means formed with a needle-passage and sustained below and close to the lower surface of said throat-plate for supporting the fold of material, whereby
15 said material is bent sharply about a sidewall portion of said aperture.
18. In a sewing machine, in combination, 20
stitch-forming mechanism including a reciprocating needle, feeding mechanism, a throat-plate having a needle aperture through which a strip to be stitched passes upwardly, and pull-off means acting upon

said strip between the needle aperture and the source of supply.

19. In a sewing machine, in combination, 25
stitch-forming mechanism including a reciprocating needle, four-motion feeding mechanism, a throat-plate having a needle aperture through which a strip to be stitched passes upwardly, and means whereby an 30
element of said feeding mechanism serves as a pull-off for said strip prior to a feeding stroke.

20. In a sewing machine, in combination, 35
stitch-forming mechanism including a reciprocating needle, feeding mechanism including a feed-bar, a throat-plate, and spaced strip-guiding elements below the work engaging surface of said throat-plate, said feed-bar being adapted to engage and deflect said strip between said elements.

In testimony whereof, I have signed my name to this specification.

ALBERT H. DE VOE.
